CLAIM

The ornamental design for confection, as shown and described.

DESCRIPTION

FIG. 1 is an enlarged top view of confection, showing our new design;

FIG. 2 is a lateral view (left side) thereof;

FIG. 3 is a lateral view (right side) thereof;

FIG. 4 is a front view thereof;

FIG. 5 is a rear view thereof; and,

FIG. 6 is a bottom view thereof.

The dashed lines showing of the boundaries within the surface ornamentation of the ears, eyes and mouth are for the purpose of illustrating unclaimed portions and form no part of the claimed design.
